UNITED STATES PATENT OFFICE.

SIDNEY W. COLE, OF CENTRE ROAD STATION, PENNSYLVANIA.

SAW-MILL DOG.

SPECIFICATION forming part of Letters Patent No. 371,552, dated October 18, 1887.

Application filed November 23, 1886. Serial No. 219,730. (No model.)

To all whom it may concern:

Be it known that I, SIDNEY W. COLE, of Centre Road Station, in the county of Crawford and State of Pennsylvania, have invented 5 a Saw-Mill Dog, of which the following is a specification.

The invention will first be described in connection with the drawings, and then pointed out in the claims.

10 Figure 1 of the drawings is a front, and Fig. 2 a rear, elevation.

In the drawings, A represents the standard; B, the dog; C, a notched latch; D, a sliding head which carries the knife; E, a spring having a shoulder which engages the shoulder K on the head; F, a handle by which the head is raised; G, a ball on the top of spring E; H, a stop on the upper end of standard, and J 15 J stops at the lower end, whereby the up-and-down movement of the slide D may be regulated.

The latch C has notches C'', C''', and C'''' and handle C', so that the notches may receive the pin L and hold the arm of dog B at any 20 point to which it may be slid through the head D, thus adapting the position of the knife to the size of the saw-log. The standard has holes M for convenience in attaching the dog to a knee.

25 30 The saw-log having been placed under the

dog B, the workman presses the ball on the upper end of spring, when the latter ceases to support the head D and it descends with accelerating force, driving the knife into the log, where the weight of the head is quite sufficient to hold it. The spring works back and forth in the guide and keeper I on the standard. 35

I am aware that a sliding head has been provided with a pawl and combined with a ratcheted standard; but

What I claim as new, and desire to protect by Letters Patent, is—

1. A saw-mill dog consisting of the standard A, head D, sliding thereon, a dog, B, on said head, and a spring, E, which engages a shoulder of head, whereby the head is supported and tripped, as described. 45

2. The combination, with the sliding head D, arranged on a standard and provided with a side pin, L, of a dog, B, having a handle movable through said head, and a lever-latch, C C', pivoted to one side of the dog-handle and having notches to fit over said pin L, whereby the dog may be adjusted, as set forth. 50 55
